UNITED STATES PATENT OFFICE.

WAYNE F. PALMER, OF WASHINGTON, DISTRICT OF COLUMBIA.

CIRCUIT BREAKER.

Application filed May 13, 1920. Serial No. 381,288.

To all whom it may concern:

Be it known that I, WAYNE F. PALMER, a citizen of the United States, residing at Washington, District of Columbia, have invented new and useful Improvements in Circuit Breakers, of which the following is a specification.

This invention relates to circuit breakers and will hereinafter be described with relation to its application to breaking the electrical circuit in a submarine mine in order to prevent countermining, although it is, of course, understood that it is applicable to other uses, and with slight modifications, as will be hereinafter explained, could be adapted to affect mechanically the firing mechanism to prevent operation thereof under similar circumstances.

One of the objects of the present invention is to provide a reliable and efficient circuit breaker of the above character which may be inexpensively manufactured and assembled.

A further object is to provide a simple and practical circuit breaker of the above type which may be easily controlled, adjusted and set for predetermined requirements.

A further object is to provide certain safety features and safety devices to prevent countermining with more certainty than has heretofore been possible.

A further object is to provide an efficient circuit breaker which will be active over a long period and whose usefulness will not be determined by a spring mechanism or other exhaustible means.

A further object is to provide an efficient circuit breaker that will function continually through a series of countermining blows and whose protection will be additive.

Other objects will be in part obvious and in part hereinafter pointed out.

One of the various possible embodiments of the invention is shown in the annexed sheet of drawings, forming a part of this specification, wherein a single figure illustrates the complete circuit breaker in longitudinal section.

Referring now to this drawing in detail, a main body member 1 of metal or other suitable material is adapted to be secured in any desired manner as by screw threads 2 into the shell of the main casing 3. This body member is provided at its lower part with a flange 4 on which a ring 5 is seated.

This ring is provided with screw threads 6 into which a tubular member 7 is threaded and provided with suitable packing means 8 and 10 as may be necessary to insure a liquid tight connection. The upper part of the body member is provided with a perforated spider 11 threadedly connected at 12 with the body member 1 and carries a protecting casing 14 at the top. The spider member 11 is provided with a sleeve 15 through which slides the diaphragm supporting member 16 which in turn supports a flexible diaphragm 17 the outer edge of which is clamped between the spider 11 and body portion 1. A nut 18 holds the central part of the diaphragm in place. The upper part of the member 16 is threaded and provided with lock nuts 20 which permit a convenient adjustment for limiting the movement of the member 16 when subjected to pressures. Likewise, the threaded sleeve 15 also permits an adjustment of the diaphragm to the desired pressure corresponding to the estimated pressure which will be exerted upon the mine when at a predetermined depth. At the top of the member 16 is a threaded screw or other plug 21 for filling the chamber beneath the diaphragm which is encompassed by a collapsible metallic bellows 22. The opposite ends of the tubular member are closed at one end by means of threaded cap 23 which supports a valve member 24 normally held in closed position by spring 25 acting between the head of the valve and a seat 26. Secured to this member 23 is a second metallic bellows member 27, the opposite end of which rests upon a ring 28 supported by a stem 30. This stem 30 passes through a cap 31 closing the lower end of the tubular member 7 and is provided with a central opening through which the outer end of the stem passes. This end carries a contact member 32 adapted to electrically connect two contact points 33 held in yielding engagement therewith by springs 34. Opposite binding posts 35 are connected with a firing circuit 36 including diagrammatically a battery 37, a firing mechanism 38 and a detonator 39. A suitable protecting cover 40 is employed to keep the contacts clean and dry under the circumstances. A spiral spring 41 surrounding the stem 30 and acting between the cup-shaped member 31 and plate 28 normally urges the metallic bellows 27 upwardly to hold a tubular member of sleeve

42 in engagement with the under side of the member 26 of the valve casing.

It will be understood that both metallic bellows or the chambers formed thereby are filled with any desired fluid, such as kerosene, which does not have a corrosive action upon the metals and which will not freeze at low temperatures.

Before going into a statement of the operation of the device, it may be stated that in countermining operations a relatively large charge is exploded in the vicinity of the mine and the disturbance resulting therefrom is transmitted to the firing mechanism in such a way as to produce a premature explosion of the mine. An under-water explosion acts in two ways, the first result of the explosion is a wave radiating out from the charge with a resultant concussive effect like a greatly increased hydrostatic pressure. It is followed almost immediately, but still with a perceptible delay, by a force driving out radially, which causes the water to act as a projectile. It is this force which will tear the hull of a ship and against which a nearby mine must be proof. The first of these forces is utilized by this invention to prevent premature firing due to the second of the two forces. In other words, the detonating of a large mass of explosive beneath the water produces two independent effects, separated by a small interval of time and it is during this interval of time that the electric circuit of the mine is broken, thereby eliminating any possible action of the detonator under such circumstances.

In operation the threaded sleeve 15 is screwed down upon the upper part of the diaphragm backing member 16 to exert a compressive action on the fluid within the metallic bellows 22 corresponding substantially to the estimated hydrostatic pressure that will be exerted thereon when the mine is submerged to a predetermined depth. The adjusting nuts 20 are then moved to the proper position to provide a limited amount of play between this sleeve 15 and the lower nut 20. The pressure exerted on the liquid within the metallic bellows 22 will, of course, be transmitted through the spring actuated valve 24 to produce a corresponding pressure upon the liquid therein. The spring 41, however, is so tensioned as to hold the stop member 42 in engagement with the under side of the valve member even at this adjusted compression. The small compression of spring 41 due to errors in setting sleeve 15 and the resultant tendency of the bridge 32 to break electric connection is absorbed by spring contacts 33. The ratio between the diaphragm 17 and the diaphragm 27 may be varied as desired. It is preferred, however, that this ratio should be about five to one so that moving of the diaphragm 17 downward one-tenth of an inch will pro-

duce a movement of the diaphragm 27 five times that amount or one-half of an inch. When a countermining operation is undertaken the initial effect of the explosion, or the first compressive action on the water around the mine, will move this diaphragm 17 downward at least one-tenth of an inch thereby increasing the pressure on the liquid therein. This pressure is transmitted through the valve member 24 to the inner metallic bellows and causes a downward movement of the diaphragm 27 a proportional amount thus carrying the contact member on bridge piece 32 out of engagement with the yielding contacts 33.

Should the mine now be subjected to any force that might tend to fire it prematurely, it will be without effect. After the passing of the countermining disturbances, the pressure in the vicinity of the mine will return to the normal hydrostatic pressure. Diaphragm 17 will tend to return to the normal and the liquid in bellows 22 and 27 will likewise tend to return to the external hydrostatic pressure. This return to a condition of equilibrium is, however, delayed for a predetermined time by seepage valve 24. The bridging of the two electric contacts 33 by member 32 is delayed and the mine continues safe until normal conditions exist.

It is believed from the above that the construction, the method of use, and the operation will be clear to those skilled in the art and a further statement thereof is doubtless unnecessary. It will also appear clear that the mechanism is not to be limited to its application to break an electrical circuit, for it is obvious that any movement of the bridge piece 32 might be transmitted mechanically to the firing mechanism to render the same inoperative.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and, therefore, such adaptations should and are intended to be comprehended within the meaning and range of equivalency of the following claims.

What I claim is:—

1. In a device of the character described, in combination, firing mechanism communicating chambers adapted to be filled with liquids, a diaphragm associated with each of said chambers in such ratio that a movement of one diaphragm will cause a corresponding movement of the other diaphragm and means associated with one of said diaphragms adapted to be moved thereby and render the firing mechanism of a mine inoperative.

2. In a device of the character described, in combination, two chamberlike members arranged in operative relation to each other, one having a collapsible diaphragm, the other rigid, and communicating one with the other, a member associated with one of said diaphragms and adapted to be moved thereby, said diaphragms being so proportioned that a relative movement of one diaphragm 10 will cause a corresponding increase movement of said other diaphragm and the parts connected therewith.
3. In a device of the character described, in combination, two chamberlike members arranged in operative relation to each other, each having a diaphragm and communicating one with the other, a member associated with one of said diaphragms and adapted to be moved thereby, said diaphragm being so 20 proportioned that a relative movement of said other diaphragm and the parts connected therewith, and means for adjusting the extent of movement of one of said diaphragms.
4. In a device of the character described, in combination, an electrical circuit having a movable circuit breaking member, two chamber-like members associated with each other, a diaphragm associated with each 25 chamber, one of said diaphragms being connected with said circuit breaking member, said diaphragms being so proportioned that a slight movement of the larger diaphragm will cause a correspondingly increased movement of the second diaphragm and the 30 circuit breaking member associated therewith.
5. In a device of the character described, in combination, two chamber-like members associated one within the other, diaphragms 40 associated with each member, collapsible metallic bellows connecting said diaphragms, a valve interposed between said members whereby a fluid may pass freely from one to the other in one direction, a circuit breaking member connected with one of said 45 diaphragms whereby a movement of one diaphragm will cause a proportional movement of the other diaphragm and the circuit breaking member associated therewith.
6. In a device of the character described, in combination, two chamber-like members associated one within the other, diaphragms 50 associated with each member, collapsible metallic bellows connecting said diaphragms, a valve interposed between said members whereby a fluid may pass freely from one to the other in one direction, a circuit breaking member connected with one of said 55 diaphragms whereby a movement of one diaphragm will cause a proportional movement of the other diaphragm and the circuit breaking member associated therewith.
7. In a device of the character described, 60 in combination, two chamberlike members arranged in operative relation to each other, one having a collapsible diaphragm and the other rigid, and communicating one with the other, a member associated with one of said diaphragms and adapted to be moved thereby, said diaphragms being so proportioned that a relative movement of one diaphragm will cause a proportional movement of the other diaphragm and the circuit breaking member associated therewith and means for restoring said parts to normal condition.
8. In a device of the character described, 70 in combination, two chamber-like members associated one within the other, diaphragms associated with each member, collapsible metallic bellows connecting said diaphragms, a valve interposed between said members whereby a fluid may pass freely from one to the other in one direction, a circuit breaking member connected with one of said diaphragms whereby a movement of one diaphragm will cause a proportional movement of the other diaphragm and the circuit breaking member associated therewith and means for adjusting the extent of movement of said diaphragms.
9. In a device of the character described, 80 in combination, a firing mechanism, a body member forming a chamber, a metallic bellows and diaphragm within said chamber adapted to be subjected to hydrostatic pressures, a second chamber having a metallic 85 bellows and diaphragm associated therewith, a valve connection between said chambers through which pressure is transmitted from one to the other and a member adapted to be associated with a firing mechanism of 90 a mine adapted to be moved on movement of said second diaphragm.
10. In a device of the character described, 95 in combination, a firing mechanism, a body member forming a chamber, a metallic bellows and diaphragm within said chamber adapted to be subjected to hydrostatic pressures, a second chamber having a metallic 100 bellows and diaphragm associated therewith, a valve connection between said chambers through which pressure is transmitted from one to the other and a member adapted to be associated with a firing mechanism of 105 a mine adapted to be moved on movement of said second diaphragm.
11. In a device of the character described, 110 in combination, a body member forming a chamber, a metallic bellows and diaphragm within said chamber adapted to be subjected to hydrostatic pressures, a second chamber having a metallic 115 bellows and diaphragm associated therewith, a valve connection between said chambers through which pressure is transmitted from one to the other and a member adapted to be associated with a firing mechanism of a mine adapted to be moved on movement of said second diaphragm, said diaphragm being of different size whereby the movement of said last mentioned member is proportional to the movement of said first mentioned diaphragm.
12. In a device of the character described, 120 in combination, a body member forming a chamber, a metallic bellows and diaphragm within said chamber adapted to be subjected to hydrostatic pressures, a second chamber having a metallic bellows and di- 125
13. In a device of the character described, 130 in combination, a body member forming a chamber, a metallic bellows and diaphragm within said chamber adapted to be subjected to hydrostatic pressures, a second chamber having a metallic bellows and di-

aphragm associated therewith, a valve connection between said chambers through which pressure is transmitted from one to the other and a member adapted to be associated with a firing mechanism of a mine adapted to be moved on movement of said second diaphragm, said diaphragm being of different size whereby the movement of said last mentioned member is proportional to the movement of said first mentioned diaphragm, and means for adjusting said diaphragm to an initial hydrostatic pressure.

12. In a device of the character described, in combination, a firing mechanism, a body member forming a chamber, a metallic bellows and diaphragm within said chamber adapted to be subjected to hydrostatic pres-

20 sures, a second chamber having a metallic bellows and diaphragm associated therewith, a valve connection between said chambers through which pressure is transmitted from one to the other and a member adapted to be associated with a firing mechanism of a mine adapted to be moved on movement of said second diaphragm, said diaphragm 25 being of different size whereby the movement of said last mentioned member is proportional to the movement of said first mentioned diaphragm, and means for limiting the movement of said first mentioned dia- 30 phragm.

Signed at Washington, District of Columbia, this 9th day of December, 1919.

WAYNE F. PALMER.
